STOVE

Stephen L. Rogers, Jr., 400 Magnolia Ave., and James Leonard Raulston, 800 Holly Ave., both of South Pittsburg, Tenn.

Filed June 20, 1963, Ser. No. 75,452

Term of patent 14 years

(Cl. D81—19)

FIG. 1

FIG. 2

FIG. 3

FIG. 4

FIG. 5

FIG. 1 is a perspective illustrating the design of the present invention with the front doors closed;

FIG. 2, a front elevation with the doors open with the portions disclosed in broken lines for illustrative purposes only;

FIG. 3, a rear elevation;

FIG. 4, a side elevation; and

FIG. 5, a fragmentary detail section taken on the line 5-5 of FIG. 3.

The side not shown is substantially a mirror image of the side illustrated in FIG. 4.

We claim:

The ornamental design for a stove, as shown and described.
